US0D1054999S

(12) **United States Design Patent** (10) **Patent No.:** **US D1,054,999 S**
(45) **Date of Patent:** **** Dec. 24, 2024**

(54) **CHARGING CABLE FOR A COMPUTING DEVICE**

(71) Applicant: **Urban Armor Gear, LLC**, Laguna Niguel, CA (US)

(72) Inventor: **Evan Hong**, Murrieta, CA (US)

(73) Assignee: **Urban Armor Gear, LLC**, Laguna Niguel, CA (US)

(**) Term: **15 Years**

(21) Appl. No.: **29/897,622**

(22) Filed: **Jul. 17, 2023**

(51) LOC (14) Cl. **13-03**

(52) U.S. Cl.

USPC **D13/147**

(57) **CLAIM**

The ornamental design for a charging cable for a computing device as shown and described.

DESCRIPTION

FIG. 1 is a front perspective view of one embodiment of a charging cable for a computing device of my new design. FIG. 2 is a front plan view of the charging cable of my new design illustrated in FIG. 1.

FIG. 3 is a rear plan view of the charging cable of my new design illustrated in FIG. 1.

FIG. 4 is a side plan view of the charging cable of my new design illustrated in FIG. 1.

FIG. 5 is an opposite side plan view of the charging cable of my new design illustrated in FIG. 1.

FIG. 6 is a top plan view of the charging cable of my new design illustrated in FIG. 1; and,

FIG. 7 is a bottom plan view of the charging cable of my new design illustrated in FIG. 1.

Any broken lines in the drawings illustrate portions of the charging cable for a computing device that form no part of the claimed design.

1 Claim, 4 Drawing Sheets
